UNITED STATES PATENT OFFICE.

CLARENCE A. VETTER, OF PITTSBURGH, PENNSYLVANIA.

ATTACHMENT-PLUG.

1,299,271.

Specification of Letters Patent.

Patented Apr. 1, 1919.

Application filed April 10, 1915. Serial No. 20,426.

To all whom it may concern:

Be it known that I, CLARENCE A. VETTER, a resident of Pittsburgh, in the county of Allegheny and State of Pennsylvania, have 5 invented a new and useful Improvement in Attachment-Plugs, of which the following is a specification.

This invention relates to attachment plugs, and particularly to what are known as 10 swivel plugs.

The object of the invention is to provide a very cheap and simple attachment plug, which has no loose parts which are liable to become lost, which can be readily attached 15 to the conductor wires, which relieves strain on the binding screws, and which can be made at low cost and is not liable to get out of order.

Further objects of the invention are in 20 part obvious and in part will appear more in detail hereinafter.

The invention comprises the attachment plug hereinafter described and claimed.

In the drawings, Figure 1 represents a 25 side elevation of an attachment plug embodying the invention; Fig. 2 is a longitudinal sectional view thereof; Fig. 3 is a longitudinal section on the line 3—3, Fig. 2, looking in the direction of the arrows; and 30 Fig. 4 is an end view of the base looking directly at the binding screws.

The plug shown in the drawings comprises two members, a base 1 and a cap 2, which are preferably made of porcelain, 35 composition, fiber, hard rubber or any other suitable non-conducting material.

The base 1 has one end rounded to enter the lamp socket to which the plug is to be attached. Its upper end is cut off square 40 and is also hollowed out or recessed to provide two opposite side cavities, marked 3 and 4, separated by a thin longitudinal wall 5, which prevents short circuits between the plug terminals, and which wall connects the 45 two triangular solid side portions 6 at the upper end of the plug. The base also carries two current conducting members, marked 7 and 8 respectively, which are formed of suitable conducting material, such as brass or 50 other metal. These members are molded in the base 1 during the manufacturing thereof, and are preferably made of sheet or plate metal with openings 9 therein to receive portions of the material of the base to prevent 55 said members from pulling out endwise from the base.

One end of the conducting member 7 projects from the rounded end of the base and is bent over flat at its center to form the end contact of the plug. The other end of said member extends into the cavity 3 and is there provided with a binding screw 11 for securing one of the conductor wires 12 thereto.

The other conducting member 8 terminates at one end within the body of the base 1. Its opposite end extends into the cavity 4, where it is provided with a binding screw 13 for the other conductor wire. Beyond the binding screw member 8 is forked or 70 bifurcated substantially in Y-shape, as shown in Fig. 3, to form two arms or extensions 14, the outer ends of which are bent over flat and lie in shallow grooves in the flat ends of the triangular portions 6 of the base 75 and form a portion of the circuit connections to the other contact of the plug.

The second contact of the plug is the usual hollow screw-threaded shell 15, which surrounds the base and closes the cavities 3 and 4 and is made of pressed metal with a portion of said shell molded into the material of the cap, so that the shell is in effect an integral part of the cap. As shown, the shell has an upwardly extending annular 85 wall 16 terminating in an outwardly extending rim or flange 16^a embedded in the cap so that it will not accidentally pull out. The annular rim need not be continuous around the entire periphery and may be 90 merely a series of ears or tongues struck or bent up from the end of the cap, as will be readily understood. The cap is also provided with a central opening 17 for the conducting cord or wires and with an inner enlarged chamber 18 to receive a knot in said wires for relieving the strain from the binding screws. The wall of the shell 15 is also provided with an inwardly extending annular rib or bead 19 to coöperate with a shallow annular groove 20 in the base 1.

In assembling the plug the cap 2 is slipped over the end of the conducting wires which are then knotted and attached at their free ends to the binding screws 11 and 13. The 105 cap 2 is then pushed up over the base, the annular bead 19 being forced over the end of said base and into the annular groove 20 thereof. The internal diameter of the bead 19 is just a little smaller than the external diameter of the base 1, so that a little extra force is necessary to overcome the fric-

tion and push the bead over the end of the base and into the annular groove. The bead and groove form a swivel connection between the cap and base, enabling the plug to be screwed into a socket without turning the base, and also prevent accidental separation of the two members when the plug is disconnected from the socket. Electrical connection between the shell 15 and terminal 13 is provided by the arms or extensions 14 of the member 8, which lie near the periphery of the base 1, and when the cap 2 is screwed into a socket are forced tightly into engagement with an inwardly extending flange or wall 21 of the shell 15.

This plug is very simple, as it comprises only two parts and therefore to a large degree prevents loss of the parts. It can also be made very cheaply and is a simple and efficient form of attachment plug. It can be readily attached to the conducting wires without special tools or implements, relieves all strain of the wires on the binding screws, and can be readily manipulated by merely pulling the cap off from the base to expose the binding screws for disconnection at any time.

What I claim is:

1. An attachment plug comprising a base having a central end terminal molded therein, a cap having a screw shell molded therein, a second terminal member molded in the base and adapted to normally contact the screw shell, binding screws on the terminal members, and means to hold the cap and base together.
2. An attachment plug comprising a base having a central end terminal molded therein, a cap having a screw shell molded therein, a second terminal member molded in the base and adapted to normally contact the screw shell, binding screws in recesses in the base on the terminal members, and means to hold the cap and base together.
3. An attachment plug comprising a base having a central end terminal molded therein, a cap having a screw shell molded therein, a second terminal member molded in the base and adapted to normally contact the screw shell, binding screws on the terminal members, and means to hold the cap and base together in swiveling relation.
4. An attachment plug, comprising a base having two current conducting members molded thereinto, one of said members forming an end contact, said base being provided with oppositely disposed cavities, said conducting members having portions extending into said cavities, and a cap con-

nected to the base by an angular rib on the cap and a coöperating groove in the base and carrying a shell contact.

5. An attachment plug comprising a base having two terminal current conducting members molded therein, one of said members forming an end contact, oppositely disposed cavities in the base, extensions from the two terminal members into the two cavities respectively, binding screws on the extensions, and a cap carrying a screw shell adapted to slip over the base and to electrically connect the screw shell and the terminal member in the base not forming the end contact.

6. An attachment plug comprising a base having a central terminal member molded therein, said member having a projecting portion with a binding screw thereon in a cavity in the base, a second terminal member molded in the base and having a projecting portion with a binding screw thereon in another cavity in the base, an annular depression in the base, and a cap carrying a screw shell adapted to fit over the base and having an interior rib on the screw shell adapted to engage the depression in the base to make electrical contact with the conducting member therein and to hold the base and cap in swiveling engagement.

7. An attachment plug comprising a cap carrying an integral screw shell, a base carrying an end contact molded therein, and a resiliently interlocking projection and depression between the base and screw shell providing a swiveling engagement between the cap and base.

8. An attachment plug comprising a rotatably connected base and cap, a center terminal contact member molded into the base, a second terminal member molded into the base, a screw shell molded into the cap, and means to electrically connect the screw shell to the second terminal member.

9. An attachment plug, comprising a base having a central terminal contact member molded therein, a cap having a threaded outer contact shell member molded therein, and means to retain the cap and base in rotatable connection comprising a rib on one and an annular groove on the other adapted to be engaged and disengaged by forcing the rib into and out of the groove.

In testimony whereof I have hereunto set my hand.

CLARENCE A. VETTER.
